UNITED STATES PATENT OFFICE

2,592,570

STAPLE EXTRACTOR

Robert Hofstetter, Alexandria, Va.

Application August 31, 1949, Serial No. 113,441

1 Claim. (Cl. 254—28)

(Granted under the act of March 3, 1883, as
amended April 30, 1928; 370 O. G. 757)

1

The invention described herein may be manufactured and used by or for the Government of the United States for governmental purposes without payment to me of any royalty thereon in accordance with the provisions of the act of April 30, 1928 (ch. 460, 45 Stat. L. 467).

This invention relates to devices for extracting sheet-binding staples and particularly to one in which opposed pairs of overlapping claws are initially forced between a sheet and a binding staple followed by a retraction of one pair of claws with respect to the relatively stationary claws.

In the accompanying drawings illustrative of a preferred form of my device,

Figure 1 is a side elevation of my device in initial staple-straddling position.

Figure 2 is a side elevation, in final position showing an extracted staple prior to discharging the same.

Figure 3 is a bottom view of my device with the claws in initial position.

Figure 4 is a section on the line 4—4 of Figure 1.

In these drawings:

A pair of staple-engaging claws 11, 11 are integral with a housing 12 forming a handle for the device, a second pair of claws 13, 13 are adapted to telescopically engage said claws 11, 11 and are integral with a guiding cam 14. The cam portion is preferably U-shaped in cross section and may have identical cams 14, 14 on each leg, while one or both of the legs of the U are slotted as at 15. A lower transverse pin 16, preferably within a roller 17, which may also serve as a spacer, is mounted transversely of the housing 12 and provides an abutment against which the cam 14 is forced during the operation of my device. Around the roller 17 is a coiled spring 18 having an arm 19 bearing against the housing 12 and another arm 20 bearing against a transverse pin 21 which is mounted in and spans the cam members 14, the arm 20 extending outwardly from the claws 13 as shown in Figure 3. The slots 15, 15 receive a second transverse pin 22 which is mounted in and spans the housing 12 for assisting in guiding the cams 14, 14. Each extension of the pin 21 is initially in contact with a shoulder 23 of the housing 12 but after the staple is engaged by the claws 13 the pin 21 moves into two recesses 23A. For distributing the pressure applied by the operator's thumb there is rigidly attached to the cam member 14 a button 24 preferably similar to those in common use on typewriters.

2

In operation, my device may be grasped in one hand with a thumb on the button 24 and pressed against sheets 25 to be separated with the claws 13 and 11 straddling a wire staple 26 and is 5 squeezed, which initially forces the claws 11 and 13 between the sheets 25 and the staple 26 and because they are arranged to telescope they jointly put pressure on the staple 26. As the squeezing is continued the cam 14, in riding on the roller 10 17, is bodily reciprocated with respect to the companion housing member 12 and thereby draws the staple 26 out of the sheets 25 as the staple prongs are straightened. Thus, the staple is 15 quickly extracted without mutilating the sheets 25.

It should be understood that the present disclosure is for the purpose of illustration only, and that the invention includes all modifications and equivalents which fall within the scope of the 20 appended claim.

What is claimed is:

In a portable staple extracting device, the improvement which comprises a housing forming a handle provided with two spaced claws merging 25 into staple arresting abutments, a pin supporting shoulder and a pin receiving recess, a pair of opposed claws rigidly connected with a U-shaped member provided with a cam face and a longitudinal slot retractably mounted within said handle, a pressure distributing button rigidly secured 30 to said retractable member, a transverse pin mounted in said retractable member and extending laterally to engage said shoulder of said handle, a transverse cam engaging pin mounted in said housing, a coiled spring mounted on said cam engaging pin having oppositely extending arms one of which bears against said housing while the companion arm bears against said transverse pin in said retractable member, and a second transverse pin in said housing which is 35 mounted transversely to said retractable member and engages the slot in said member.

ROBERT HOFSTETTER.
